No. 869,764.

PATENTED OCT. 29, 1907.

W. G. ANDERSON.
HEEL FOR BOOTS AND SHOES.
APPLICATION FILED OCT. 11, 1906.

UNITED STATES PATENT OFFICE.

WILLIAM G. ANDERSON, OF BROOKLINE, MASSACHUSETTS, ASSIGNOR TO NELLIE S. ANDERSON, TRUSTEE, OF BROOKLINE, MASSACHUSETTS

HEEL FOR BOOTS AND SHOES.

No. 639,764.

Specification of Letters Patent.

Patented Oct. 22, 1907.

Application filed October 11, 1906. Serial No. 338,337.

To all whom it may concern:

Be it known that I, WILLIAM G. ANDERSON, a citizen of the United States, residing at Brookline, in the county of Norfolk and State of Massachusetts, have invented new and useful Improvements in Heels for Boots and Shoes, of which the following is a specification.

This invention relates to improvements in resilient heels for boots and shoes and especially to improvements in heels for boots or shoes of the general class disclosed in U. S. Letters Patent No. 582,336, granted to me May 7, 1897. In the use of the heel disclosed in said patent two practical objections were met with; mud collected in the recess formed in the under side 15 of the heel and was carried into houses and tracked over the floors and carpets, and also the diaphragm failed to move when the heel was subjected to the weight of the wearer, thereby preventing a perfect section.

20 This invention aims to overcome these practical objections and in practice has been found to accomplish the result sought for, viz., to keep the recess free from mud and to prevent the slipping of the heel on wet or icy pavements.

25 The invention consists in a heel formed of resilient material, such as rubber, as described in the following specification and particularly pointed out in the claims thereof.

Referring to the drawings: Figure 1 is an underneath 30 plan view of my improved heel for boots and shoes. Fig. 2 is a section on line 2—2 of Fig. 1, looking toward the right in said Fig. 1. Fig. 3 is a central longitudinal section of the same shown attached to a shoe, said shoe being broken away to save space in the drawings and 35 the heel resting upon the pavement, said shoe being indicated in dotted lines. Fig. 4 is a section similar to Fig. 3 but with the recess in the under side shown filled with mud, the heel being shown compressed by the weight of the user thereon.

40 Like numerals refer to like parts throughout the several views of the drawings.

In the drawings, 5 is a heel formed of resilient material, preferably rubber. The heel 5 is provided with a recess 6 in the upper side thereof and with a recess 7 in the under side thereof, the recess 6 being the upper recess and the recess 7 the lower recess, the material between said upper and lower recesses constituting a diaphragm 8. A rib 9 depends from the diaphragm 8 and extends across the lower recess 7. While I have 45 shown the rib 9 extending entirely across the recess 7, I may, if I so desire, extend said rib only partly across said recess.

The heel 5 is applied to a shoe 10 in the usual manner by means of nails 11. The under side of the heel, before being applied to the shoe, is flat throughout and the upper side thereof is concave and is so formed that

when the heel is applied to the shoe the nails with which the heel is applied draw the middle portion of said heel upwardly, so that the under side thereof becomes slightly concave, as is clearly shown in Figs. 2 and 3. 50 It will be noted that the heel is of greater depth at the breast or front edge than at the rear edge, so that when the shoe is placed flat upon the ground said front edge only contacts with the ground. In taking a step, however, the wearer of the heel, of course, advances his 55 foot and places the heel upon the ground in such a position that the under side of the heel rests upon the ground throughout. When the wearer brings his weight to bear upon the heel, said heel is, of course, compressed by his weight and a small portion of the air 60 contained within the recess 7 is expelled and escapes between the under side of the heel and the ground, thereby causing a powerful suction to be formed, whereby the heel is prevented from slipping on a wet or 65 icy pavement. With each step, owing to the compression of the entire heel, due to the weight placed upon it and also to inequalities of the pavement upon which the rib 9 rests, the diaphragm 8 is continually 70 moved up and down. The air contained within the recess 6, being entirely confined is, of course, compressed when the diaphragm 8 is moved upwardly and when the heel is raised said air contained within the recess 6 expands quickly and acts to impart a sudden 75 downward movement to the diaphragm 8, thereby expelling from the recess 7 any mud which may have collected therein.

In Fig. 4 I have illustrated the recess 7 filled with mud, while in Fig. 3 I have illustrated the recess 7 free from mud after the mud has been expelled therefrom by the quick downward movement of the diaphragm 8, 80 as hereinbefore described. When the heel is lightly in contact with the floor or pavement, with but little downward pressure applied to the heel, the under side of the heel bears against the floor or pavement only at or near its periphery, so that as the downward pressure 85 is increased by the weight of the wearer, air is permitted to escape from the recess 7 past the periphery of the heel much more readily than if the under side of the heel were flat. This feature contributes to make the suction much more powerful than if the heel were 90 formed flat on its under side. It will thus be seen that the heel cannot slip upon a wet or icy pavement.

Having thus described my invention, what I claim and desire by Letters Patent to secure is:

1. A resilient heel for boots and shoes having a recess in its upper side and a recess in its lower side, the material between said upper and lower recesses being relatively thin and constituting a diaphragm, and a depending projection 105 from said diaphragm, the lower face of said projection adapted to contact with the ground or pavement when in use.

2. A resilient heel for boots and shoes having a recess in its upper side and a recess in its lower side, the material

separating said upper and lower recesses being relatively thin and constituting a diaphragm, and a rib extending across said lower recess adapted to contact with the ground or pavement when in use.

5. 3. A resilient heel for boots and shoes having a recess in its upper side and a recess in its lower side, the material between said upper and lower recesses constituting a diaphragm and having a depending projection extending from said diaphragm, the lower face of said projection adapted

to contact with the ground or pavement when in use and 10 said upper side being concave, whereby when applied to a boot or shoe said lower side is made concave.

In testimony whereof I have hereunto set my hand in presence of two subscribing witnesses:

WILLIAM G. ANDERSON.

Witnesses:

LOUIS A. JONES,
ANNIE J. DAILEY.
